WILLIAM H. TONK, OF NEW YORK, N. Y., ASSIGNOR TO WILLIAM TONK & BRO., INC., OF NEW YORK, N. Y., A CORPORATION OF NEW YORK.

COMBINED HORN AND SOUND-BOX.

1,311,300.

Specification of Letters Patent.

Patented July 29, 1919.

Application filed March 18, 1918. Serial No. 223,075.

To all whom it may concern:

Be it known that I, WILLIAM H. TONK, a citizen of the United States, residing in the city and State of New York, have invented certain new and useful Improvements in Combined Horns and Sound-Boxes for Talking-Machines, of which the following is a specification.

My invention relates to talking machines of either the disk or cylinder type and employing either the "hill and valley" or laterally undulating grooves.

It is the principal object of my invention to provide a combined horn and sound box for use with talking machines of the kind described which, when not in use, can be collapsed or folded so as to occupy very little space but which, when it is to be used, can be instantly opened up so as to constitute a horn of good tone qualities with sound box attached. It is a further object of my invention to provide a combined horn and sound box of the type described which, when not in use, can be instantly detached from its working position upon the machine, folded into flat form, and either carried in the pocket or packed into the case or mounting which contains the other parts of the machine. The collapsible feature may, however, be omitted from my invention where space is ample, as is the case with machines which are intended strictly for home use or for public halls and the like, and still present many features of advantage.

The combined horn and sound box of my invention can be very simply, easily and cheaply made and consists of but few parts. It can also be made very strongly and can readily be repaired without the exercise of any great degree of skill.

My invention will be found particularly useful in talking machines for campers and picnic parties, and on automobile trips. It is also particularly adapted to talking machines to be used in military camps and at the front. This is partly because its employment enables the entire machine to be made very inexpensively and partly because it makes for great compactness and requires but little space for storage or transportation.

My invention will be better understood by referring to the accompanying drawings, which represent a preferred form thereof as

arranged for a disk phonograph using records of the "hill and valley" type. In these drawings, Figure 1 is a plan view, part being broken away; and Fig. 2 is a front elevation, showing both the talking machine and the combined horn (in open position) and sound box; and Fig. 3 represents a central longitudinal section, enlarged, through the collapsed horn and sound box only.

In the drawings, the casing, 1, contains the motor (not shown) of any usual type arranged to drive the spindle, 2, with attached record plate, 3, upon which is mounted the record, 4, all in the usual way. The motor is provided with a crank handle, 5, for winding.

The combined horn and sound box which really constitutes my invention, comprises a hollow bottom box or tone chamber, 6, (corresponding to the usual tone arm), a thin top leaf or member, 7, hinged to the tone chamber at 8, and thin lateral members, 9, 10, on each side, respectively hinged to the tone chamber and top leaf and, also, hinged to one another on the center line, 11, along which line they may be folded inwardly, thus enabling the top leaf to be folded against the tone chamber.

The tone chamber, top leaf and lateral members are, preferably, built up of thin dried wood of varieties such as are generally employed in making musical instruments. Other materials, such as metal, celluloid, vulcanized fiber, or the like, may be used if desired. The lateral members, 9, 10, being each of stiff unyielding material, will, when brought into alinement, as in Figs. 1 and 2, remain so, and thus maintain the horn in open position.

The bottom of the tone chamber, near its front end, is provided with an opening, 12, in which is fastened a sound box, 13, of usual construction, having a diaphragm, 14, and multiplying lever, 15, pivoted at 16, for movement in a vertical plane, and having one end connected to the diaphragm and the other end carrying the needle, 17.

The top of the tone chamber has a small opening, 18, at its rear end.

The casing, 1, has a socket, 19, its top near one edge, and is adapted to receive a spindle or pivot shaft, 20, which is attached to the closed end of the horn, preferably to the top

leaf, 7. The angle of spindle, 20, is so determined with reference to the top leaf that, when the horn and sound box are in position on the casing and ready for operation, (Figs. 1 and 2), the tone chamber will be substantially horizontal.

The spindle, 20, may be permanently fastened to the horn or, preferably, may be fastened, detachably as shown in the drawings, 10 for example. Here the spindle terminates in a plate, 21, whose edges engage slidably with a shallow frame, 22, attached to the top leaf. When the machine is disassembled and the horn folded up, spindle, 20, with its 15 plate, 21, may be separately stowed away in any convenient place.

In the operation of the talking machine, the needle, 17, is vibrated in the vertical plane by the "hill and valley" grooves in 20 the usual way, thereby correspondingly vibrating the diaphragm. The sound waves are transmitted through the tone chamber, 6, and out of opening, 18, into the horn, from the open front end of which they pass 25 into the usual way.

As the record revolves, the entire horn and sound box will be guided by the record grooves so as to swing about the axis of spindle, 20, just as does the "tone arm" in 30 the conventional disk record type of machine. This necessarily correspondingly changes the position of the sound wave axis (the longer axis of the horn) but this change is comparatively unimportant, and may be 35 considered especially so in a low priced compact machine for general utility purposes such as I believe the device of my invention to be best adapted to.

To exchange records it is merely necessary 40 to lift the outer end of the lower leaf or tone chamber, 6, thus carrying sound box and needle away from the record and leaving ample space for slipping a record in and out and upon and off the spindle, 2. 45 The lower leaf may be held up by the finger while the exchange is taking place or, if lifted to its limit against the top leaf, 7, it may be locked and held in this position by the spring catch, 23, provided for the purpose.

If it is desired to use the invention with records having laterally undulating grooves (the Berliner form) then the spindle, 20, may be attached to the horn so as to be 55 parallel with the hinge, 8, thereof instead of at right angles thereto, as shown in Figs. 1 and 2, and above described. The horn will then be positioned "edge on", so to speak, when in operative position. Or, the horn 60 may remain in substantially the same operative position, relative to the motor casing, as has been illustrated and described above in connection with the "hill and valley" grooves provided the sound box itself be 65 suitably mounted upon the tone chamber.

Thus, with a sound box of the construction as shown in Figs. 1 and 2, if the horn be tilted up so as to bring the front end of the tone chamber nearer the sound record than the rear end, and if the sound box be set 70 with the plane of the multiplying lever transverse to the length of the horn instead of parallel therewith, the needle will be at an angle with the surface of the record instead of normal thereto; under such circumstances, the needle will respond very nicely 75 to the lateral undulations of the Berliner type. Even with the tone chamber left parallel with the record disk, the results will be satisfactory, especially if the needle be given a little extra length.

While I have shown my invention with one form of sound box the same is not restricted thereto and any suitable sound box 80 may be employed.

Instead of the individually unyielding lateral members, 9, 10, I may use flexible sides of fabric, leather, or the like, for the horn. In this case some means must, of course, be provided to hold the horn open 90 when it is to be used. This may be, *e. g.*, a link pivoted to the outer end of one leaf and adapted to be engaged or disengaged with the outer end of the other leaf. Other means will readily occur to those skilled in 95 the art.

I may also, if I desire, substitute a thin but solid leaf for the hollow tone chamber. In this case the sound box diaphragm will even more literally than before, constitute a 100 part of the wall of the horn, the inner surface of the diaphragm being substantially a part of the inner surface of the horn and the outer surface of the diaphragm being part of the outer surface of the horn.

My invention may readily be adapted to talking machines of the cylinder type by merely substituting the usual positive unit and screw feed for the rotational feed employed above, *i. e.*, for the socket, 19, and 110 spindle, 20.

Other changes of detail will readily occur to those skilled in the art and may be made within the spirit of the invention and the scope of the following claims:

I claim:

1. In combination, a horn closed at one end and comprising an upper leaf and a hollow lower leaf or tone chamber connected together by folding members, the hollow 120 leaf having openings in opposite walls thereof, the opening in the inner wall being adjacent to the closed end of the horn, and a sound box mounted upon the hollow leaf with its diaphragm filling the opening in 125 the outside wall thereof.

2. As a new article of manufacture, a talking machine horn having rigid top and bottom walls hinged at one end and connected laterally by foldable walls, there being a 130

sound box mounted upon the bottom wall with its diaphragm exposed to the air inside the horn and also connected with the needle, the top wall also having a pivot shaft attached thereto and adapted to engage a suitable socket so that, in use, the lower wall will hang free from the upper wall with the nee-

dle resting upon the record disk while, when not in use, the two rigid walls may be closed upon one another for compactness.

10

In witness whereof I have hereunto set my hand.

WILLIAM H. TONK.
